Primary Examiner — Mark A Goodwin*(74) Attorney, Agent, or Firm* — Olive Law Group, PLLC(57) **CLAIM**

The ornamental design for a mower frame repair kit, as shown and described.

DESCRIPTION

FIG. 1 is a top, front and right side perspective view of a mower frame repair kit showing my new design, the kit having three separate, detachable sections;

FIG. 2 is a rear and left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front and right side perspective view showing the mower frame repair kit in its undetached state;

FIG. 10 is another perspective view thereof; and,

FIG. 11 is an enlarged view of portion 11 in FIG. 9.

The dash-dot-dash broken lines define the boundary of enlarged views and form no part of the claimed design.
